BY
Edward N. Pagekew, ^{ATTORNEY}

UNITED STATES PATENT OFFICE.

CHARLES E. GODLEY, OF DETROIT, MICHIGAN, ASSIGNOR TO EDMUND & JONES CORPORATION, OF DETROIT, MICHIGAN, A CORPORATION OF NEW YORK.

FOCUSING DEVICE.

Application filed May 26, 1922. Serial No. 563,863.

To all whom it may concern:

Be it known that I, CHARLES E. GODLEY, a citizen of the United States, and residing at Detroit, in the county of Wayne and 5 State of Michigan, have invented a new and Improved Focusing Device, of which the following is a specification.

This invention relates to means for bringing the active light-producing portion of the 10 filament of the light bulb of a projecting lamp or headlight to the focus of the reflector and to secure it in that position, and its object is to produce a focusing device which shall be simple in construction and easily 15 assembled, which will permit the light bulb to be quickly and accurately adjusted, and which will hold the light bulb in such adjusted position.

This invention consists, in combination 20 with the usual reflector and the combination sleeve in which the light bulb is mounted, of spherical clamping means to form a ball-like enlargement on the connector, and a socket on the reflector to receive the connector and 25 this enlargement. It further consists in a spherical clamping enlargement for the connector formed of a plurality of parts and in a socket for such enlargement consisting of 30 a threaded thimble extending rearwardly from the reflector and a nut screwed onto the thimble and formed to grip the spherical clamping enlargement so as to rigidly attach the connector sleeve and the light bulb therein to the reflector. It also consists in 35 the details of construction illustrated in the accompanying drawing and particularly pointed out in the claims.

In the accompanying drawing, Fig. 1 is a rear elevation of a reflector provided with 40 this improved focusing device. Fig. 2 is a central longitudinal section thereof. Fig. 3 is a plan of the locking nut. Fig. 4 is an end view and Fig. 5 is a plan of the spherical clamping members. Fig. 6 is an end view 45 and Fig. 7 is a plan of the connector sleeve. Fig. 8 is an end view and Fig. 9 is a plan of another form of connector sleeve.

Similar reference characters refer to like parts throughout the several views.

50 The reflector 1 shown in the drawing may be of the usual paraboloidal type or any other desired configuration which is most effective when the active light-giving position of the filament 2 of the light bulb 3 is at some fixed or focal point. Because of

the irregularities of manufacture, this portion of the filament is not always in the axis of the base 4 of the bulb nor at the same distance therefrom, so it is desirable that the filament 2 may be adjustable not only longitudinally but transversely of the axis of the reflector 1.

The connector sleeve 5 is of any desired construction, that shown being formed with bayonet slots 6 to receive the pins 7 on the base 4. On the reflector and attached thereto in any desired manner is a thimble 8 having a threaded outer end to receive the locking nut 9, which is perfectly formed with a knurled band 10 and with a spherical portion 11. The clamping device for the connector 5 is in the form of a plurality of short segments 12, three being shown in Figs. 4 and 5, the ends of which are cylindrical to fit the connector 5 while their middle portions constitute a zone of a sphere when fitted on the connector. As connectors are practically all of standard diameter, these clamping members 12 can be produced in 70 quantities.

The spherical portion 11 of the locking nut fits these clamping members. It will be noticed in Fig. 2 that the inner diameter of the outer end of the thimble 8 is less than the outer diameter of the ball on the connector 75 formed by these clamping members. It may be said that this thimble, the locking nut and the clamping members constitute a ball-and-socket joint between the connector and the reflector.

The connector is preferably formed with a small boss 14 to prevent it from slipping out when the locking nut is turned back to relieve the clamping members so that the light bulb may be properly focused. After 95 the light bulb has been slid longitudinally and swung laterally to bring the light giving portion of the filament 2 to proper position, the locking nut is screwed down to secure the parts in the desired position.

The bases of light bulbs are sometimes too loose in connectors. It is then advisable to grip them more tightly which may be accomplished by slotting the connectors longitudinally so they can be clamped onto the 105 bases of the bulbs. In Figs. 6 and 7 I have shown the connector 15 formed with a slot 16 constituting an extension of the bayonet slot 17 and extending across the end 18 of the connector. In Figs. 8 and 9 the slots 19 in 110

the connector 20 are three in number, one of them being an extension of one of the bayonet slots 21. The slots 19 do not extend to the closed end of the connector 22.

5 The details of construction and the proportions of the parts may all be changed by those skilled in the art without departing from the spirit of my invention as set forth in the following claims.

10 I claim—

1. In a focusing device for electric lamps, the combination of a reflector having an opening, a connector sleeve extending into said opening and adapted to receive a light bulb within its forward end and having a slot to permit said end to be compressed onto the base of the light bulb, compressible spherical means mounted on the connector sleeve, and means to adjustably support the

20 connector sleeve comprising a device to compress said spherical means onto the connector sleeve to secure the connector sleeve in position and thereby compress the connector sleeve onto the light bulb base.

2. In a focusing device, the combination of 25 a reflector, of a headlight, a thimble extending therefrom and having a threaded outer end, a connector extending through the thimble and adapted to receive a light bulb within its forward end, clamping members on the 30 connector, and a nut on the thimble to force the clamping members into said thimble to compress them onto the connector, said connector having a longitudinal slot to permit the connector to be compressed onto the base 35 of the light bulb.

CHARLES E. GODLEY.
